RING SPINNING FRAME

Harold S. Adams, Skowhegan, Maine, assignor to
American Woolen Company, New York, N. Y.,
a corporation of Massachusetts

Application August 30, 1947, Serial No. 771,413

5 Claims. (Cl. 57—79)

1

My invention has to do with stop motions for ring spinning machines.

In the ring spinning of yarn, the yarn is wound on bobbins in a succession of conical layers produced by successive traverses of the builder motion which after each traverse lowers the spindle rail a little. In yarn packages of this type it is also common to finish the package with a transfer end which comprises four to six turns of yarn extending from the top to the bottom of the package. This transfer end furnishes a convenient means for tying on another end of yarn. The winding of the transfer end is accomplished by the builder motion which raises the spindle rail at a rapid rate to its starting point immediately after the bobbin has been filled. It is necessary to have the machine positively stop upon the completion of the winding of the transfer end.

Heretofore, the spinning has been stopped on the completion of the package either by the operator throwing the main switch by hand at the proper moment, or by a limit switch which is operated by an adjustable element carried by the spindle rail when the spindle rail reaches its starting point after the winding of the transfer end. When the stopping is done by hand the operator, out of caution, usually stops the machine before the bobbins are completely filled, so that bobbins which are only partly filled are produced, thus losing a part of the capacity of the bobbin and of the machine and increasing the labor cost. When a limit switch is employed to stop the machine it has been found that its operating element, carried by the spindle rail, requires constant adjustment to operate effectively at the proper time under varying conditions such, for one example, as changes in spindle speed. When improperly adjusted the machine fails to stop with the result that layers of yarn are wound over the already completed package around its transfer end and these layers of yarn must be stripped off by hand with a substantial loss of labor and material.

The object of my present invention is, therefore, to provide a mechanism which will automatically stop the machine at the exact moment when the package is complete and will not overrun and start to wind again until the operator again sets the machine in motion. In the following specification I have described my invention as embodied in a ring spinning frame of the well known type in which the spindle rail is traversed by a heart cam up and down once for each conical pair of layers of yarn on the bobbin and in which there is mechanism which progressively lowers the spindle rail the entire length of the bobbin and then raises this rail rapidly to put on the few turns of yarn forming the transfer end. It will be understood that, ex-

2

cept as specifically stated, the invention is not limited to a particular type of builder motion, since it may be used in connection with machines of other types.

5 In the drawings:

Fig. 1 is a front elevation of one end of a spinning frame equipped with apparatus embodying my invention and shown partly in diagram;

Fig. 2 is a section taken on the line 2—2 of Fig. 1 with the builder motion shown partly broken away;

Fig. 3 is a section taken on the line 3—3 of Fig. 1;

Fig. 4 is a plan view of the builder motion partly in section on the line 4—4 of Fig. 2;

Fig. 5 is a section taken on the line 5—5 of Fig. 2;

Fig. 6 is a wiring diagram;

Fig. 7 is a completed package showing the transfer end; and

Fig. 8 is a similar package, such as is produced when the machine is prematurely stopped.

Referring now to the drawings, and particularly to Figs. 1 and 2, the spindle rail is shown at 14 and the ring rail at 15. The bobbins are indicated at 16 and the spindles at 17. A properly completed bobbin is shown in Fig. 7. The yarn package of this bobbin comprises a series of conical layers which are produced in the well known manner by lowering the spindle rail slightly after each traverse. The transfer end consisting of from four to six turns of yarn extending from the top to the bottom of the bobbin is shown at 12.

The builder motion is of well known construction, and, therefore, only the essential parts of it will be described. At F is shown the swinging builder frame carrying various parts. A heart cam 32 on shaft 31 which makes one revolution for each traverse raises and lowers the spindle rail. The heart cam carries a pin 100 which strikes an arm 101 of the bell crank lever k once for each revolution of the heart cam shaft 31. The other arm 102 of the bell crank lever is connected by a link 103 to the pivoted arm 104 carrying a pawl 105 which engages a ratchet wheel 106 on the outer end of a shaft 107. The shaft 107 is journaled in bearings in the builder frame F and carries at its inner end one element 108 of a dog clutch 109. The other element 110 of the clutch 109 is slidably secured to one end of a shaft 111 also journaled in bearings in the builder frame F. Slidably secured to the other end of the shaft 111 is one element 112 of a dog clutch 113. The other element 114 of the clutch 113 is secured to one end of a shaft 115 also journaled in bearings in the builder frame F. Secured to the other end of the shaft 115 is a bevel gear 116 which meshes with a bevel gear 117. Also meshing with the bevel gear 117

is a bevel gear 118 which is driven by the motor M through a worm 119 and a worm gear 120. Beneath the clutches 109 and 113 is a slide rod 121 carrying forks 122 which engage the slideable elements 110 and 112 respectively of said clutches.

Secured to the shaft 111 is a worm 130 which meshes with a worm wheel 131 carried by a shaft 132. The shaft 132 is received in bearings arranged crosswise of the builder frame above the shaft 111. Secured to the inner end of the shaft 132 is a chain pulley 133 to which a chain 134 is attached. The builder motion, through the chain 134 operates the spindle rail in well known manner. Secured to the outer end of the shaft 132 is a disk 140 to which dogs 141 and 142 are adjustably attached. Located in the path of said dogs is one arm of a lever 145 which is pivotally mounted beneath the shaft 132. The other arm of the lever 145 carries a pin 146 which is received in the groove of a member 147 secured to the slide rod 121 previously referred to.

It will thus be apparent that the heart cam 32 not only produces the traverses but, through the clutch 109, imparts intermittent motion to the shaft 132 and chain pulley 133 whereby the spindle rail is lowered step-by-step to advance the traverses and thus build the body of yarn on the bobbins.

At the same time the disk 140 is intermittently rotated to move the dog 141 step-by-step until it engages the lever 145 and turns it on its pivot to disengage the clutch 109 and engage the clutch 113. Thereafter the chain pulley 133 is driven in the opposite direction and at a higher rate of speed to return the spindle rail to its starting point. Just before the spindle rail reaches its starting point, the dog 142 carried by the disk 140 (now travelling in the opposite direction) engages the lever 145 to disengage the clutch 113 and reengage the clutch 109 to complete the cycle. It will be apparent that the location of the dog 141 on the disk 140 determines the point at which the downward movement of the spindle rail will be stopped and consequently the number of layers of yarn which will be applied to the bobbins and, therefore, the size of the packages. The mechanism so far described is old and well known in the art.

The motor M which drives the machine is in a power circuit P which is completed by its auxiliary circuit located in the starting box E. A "momentary-contact" starting switch S in the auxiliary circuit is operated by the control rod 47 through cranks 48 and a link 49 (Figs. 2 and 3). The auxiliary circuit also includes a normally-open contactor 9, an operating coil therefore indicated at 10 and a one-button "inch-stop" control station H which is provided with contacts a normally closed by a button 12 and contacts b which are normally open.

In addition there is a control circuit (see particularly Fig. 6) which is supplied with current from a transformer T. In this circuit are two switches designated No. 1 and No. 2 each of which is held normally open by a spring 70. Switch No. 1 is mounted on the builder frame F in the path of a cam 75 which is carried by the lever 145 (see particularly Fig. 4). Thus switch No. 1 is closed automatically when the lever 145 is moved on completion of winding the main body of yarn on the bobbin. This switch may also be closed manually by a hand rod 80 which is connected to the lever 145 from which it extends toward the front of the machine. Switch No. 2 is closed by a cam 85 which is adjustably

secured to the shaft 31 on which the heart cam 32 is mounted.

There are also two relays R1 and R2 in the control circuit. The relay R1 has two pairs of contacts A and B both of which are in the control circuit and are normally open. The relay R2 has one pair of contacts D which are in the auxiliary circuit of the power circuit and are normally closed.

10 The coil 60 of relay R1 is connected by wire 40 with one side of the transformer T and by wire 41, switch No. 1 (when closed) and wire 42 with the other side of the transformer. A wire 26 connects the wire 41 with one of the contacts B while the other contact B is connected by wires 27 and 23 with the wire 42. A warning signal such as a horn 95 is wired in parallel with the coil of relay R1. The coil 65 of relay R2 is connected by wires 43 and 44 with one side of the transformer and by wire 45, switch No. 2 (when closed), wire 46, contacts A of relay R1 (when closed) wire 23 and wire 42 with the other side of the transformer.

15 In operation, the machine is first adjusted to provide the proper speed for the particular size 25 of yarn to be spun, and the dog 141 positioned on the disk 140 to produce a yarn body of the required size on the bobbin. A yarn end is then 30 pinched between each bobbin and the base of the spindle upon which it rests. The control rod 35 47 is then turned in a clockwise direction as viewed in Fig. 2 to momentarily close the starting switch S. This energizes the coil 10 which 40 closes the contactor 9 after which, with the starting switch S open, the current flows through the wire 1, contactor 9, wire 2, the normally-closed contacts a in the control station H, wire 4, coil 10, wire 5, the normally-closed contacts D of relay R2 and wire 6 to complete the auxiliary circuit of the power circuit P and start the motor M.

45 Four to six windings are immediately wound on the lower ends of the bobbins. These windings, indicated at t1, Figs. 7 and 8, constitute the lower transfer ends. The first layer of yarn is then 50 wound as the spindle rail is lowered when the heart cam 32 turns through 180°. As rotation of the heart cam continues the spindle rail is 55 wound to complete the first traverse. During this action the pin 100 carried by the heart cam 32 60 operates the bell crank k which moves the lever 104 and the pawl 105 carried thereby to rotate the ratchet 106 (see particularly Figs. 2 and 5). This imparts a rotative movement to the shaft 107 which, through the clutch 109 (Figs. 2 and 4), worm 130 and worm wheel 131 rotates the 65 chain pulley 133 in the direction indicated in Fig. 2 to permit the spindle rail to drop slightly in order to advance the next traverse. This 70 process continues until the dog 141 engages the lever 145 and causes the latter to disengage the clutch 109 and engage the clutch 113. This motion of the lever 145 also causes the cam 75 carried thereby to close switch No. 1 and energize the coil 60 of relay R1 which is connected by wire 40 to one side of the transformer T and by wire 41, switch No. 1 and wire 42 to the other side of the transformer. This closes the contacts A and B of the relay R1.

75 The clutch 113 connects the chain pulley 133 with the shaft 115 by which it is now driven at a higher rate of speed in the opposite direction to return the spindle rail to its starting point. During this operation the upper transfer ends t2 are 80 applied to the packages. Just before the spindle

rail reaches its starting point the dog 142 engages the lever 145 and begins to move the latter in the opposite direction to disengage the clutch 113 and reengage the clutch 109. This permits switch No. 1 to reopen without deenergizing relay R1 the contacts A and B of which still remain closed because the coil 60 of this relay will still be connected on one side with the transformer T through wire 40 and on the other side through wire 41, wire 26, contacts B and wires 27, 23 and 42. At a predetermined point in the remaining portion of the operative cycle the cam 85 closes switch No. 2 and energizes the coil 65 of relay R2 which is connected by wires 40 and 43 with one side of the transformer and by wire 44, switch No. 2, wire 45, contacts A of relay R1 (now closed), wire 23 and wire 42 with the other side of the transformer. This opens contacts D of relay R2 to open the auxiliary circuit and thus break the power circuit to stop the machine. When the auxiliary circuit is broken, as described, the voltage is entirely removed from the control circuit. This permits the contacts D of relay R2 to close again. However the contactor 9 of the auxiliary circuit is also opened at this time and this circuit cannot be closed again until the control rod 47 is operated to close the starting switch S as previously described. Thereafter the momentum of the parts moves the spindle rail to its starting point, or approximately so, disengages the clutch 113 and reengages the clutch 109 to complete the operative cycle.

If it is necessary, for any reason, to stop the machine before the control circuit operates, this may be done by depressing the push button 12 to open the contacts *a* in the control station H. If it is desired to "inch" the machine (i. e. rotate the parts to a limited extent) for the purpose of making adjustments or for other reasons, the push button 12 is pressed inwardly to close the contacts *b* which will complete the power circuit and keep the motor running until the button 12 is released.

The control circuit, as above described, is fully automatic in its operation after the bobbins are completely filled as shown in Fig. 7. It may also be operated when the bobbins are only partially wound if it has been decided to doff the bobbins at this point because the order is filled, because a different yarn is to be added (a different yarn is tied to the transfer end 72 of each partially completed package) or for other reasons. To this end the operator pulls the hand rod 80 (Figs. 2 and 4) and thus moves the lever 145 and consequently the cam 75 to disengage the clutch 109 and close switch No. 1 in the control circuit. The control circuit then operates as previously described to stop the machine after a partially completed bobbin, such as is shown in Fig. 8, has been produced.

I claim.

1. In a ring spinning frame having a builder motion which traverses the ring rail and the spindle rail with respect to each other, the combination therewith of a power circuit, a control circuit, a relay having normally closed contacts in the power circuit and controlled by current in the control circuit, two normally open switches in the control circuit, mechanism which closes the first of said switches at a predetermined position of the spindle rail, and mechanism which closes the second of said switches after the clos-

ing of the first switch, the closing of both of said switches occurring during the last traverse of the spindle rail.

2. In a ring spinning frame having a builder motion in which a rotating member traverses the ring rail and the spindle rail with respect to each other, the combination therewith of a cam on said rotating member, a power circuit, a control circuit, a relay having normally closed contacts in the power circuit and controlled by current in the control circuit, two normally open switches in the control circuit, and mechanism which closes the first of said switches at a predetermined position of the spindle rail, the second of said switches being closed by said cam after the closing of the first switch, and the closing of both of said switches occurring during the last traverse of the spindle rail.

3. In a ring spinning frame having a builder motion which traverses the ring rail and the spindle rail with respect to each other, the combination therewith of a power circuit, a control circuit, a relay having normally closed contacts in the power circuit and controlled by current in the control circuit, and two normally open switches in the control circuit, one of which is closed in the course of the last traverse of the spindle rail, and the other of which is closed at a predetermined point in the remaining portion of said last traverse.

4. In a ring spinning frame having a builder motion which traverses the ring rail and the spindle rail with respect to each other to wind a package of yarn on a bobbin and thereafter gives the spindle rail one complete movement the full length of the bobbin, the combination therewith of a power circuit, a control circuit, a relay having normally closed contacts in the power circuit and controlled by current in the control circuit, two normally open switches in the control circuit, actuating mechanism for one of said switches comprising a cam which rotates once for each traverse, and actuating mechanism for the other of said switches including a member which makes a complete movement once during each movement of the spindle rail the full length of the bobbin, the first of said switches being closed by said member at a predetermined position of the spindle rail and the second of said switches being closed after the closing of the first switch, the closing of both switches occurring during the last traverse of the spindle rail.

5. In a ring spinning frame having a builder motion which traverses the ring rail and the spindle rail with respect to each other to wind yarn on a bobbin and in which a movable element connects the spindle rail with driving mechanism whereby the spindle rail is given one complete movement the full extent of that part of the bobbin covered by the yarn so wound, the combination therewith of a cam operated by said movable element, a power circuit, a control circuit, a relay having normally closed contacts in the power circuit and controlled by current in the control circuit, and two normally open switches in the control circuit, the first of said switches being closed by said cam and the second of said switches being closed to complete the control circuit and open the power circuit in the remaining portion of the traverse during which the first switch is closed.

HAROLD S. ADAMS.
